UNITED STATES PATENT OFFICE

101,015

DESIGN FOR AN X-RAY MACHINE

William H. Thwaites, Grand Rapids, Mich., assignor to Thwaites Ray Company, Sparta, Mich., a corporation of Michigan

Application July 13, 1936, Serial No. 63,814

Term of patent 14 years

To all whom it may concern:

Be it known that I, William H. Thwaites, a citizen of the United States, residing at the city of Grand Rapids, in the county of Kent and State of Michigan, have invented a new, original, and ornamental Design for an X-ray Machine, of which the following is a specification, reference being had to the accompanying drawing, forming a part thereof.

The figure is a perspective view of an X-ray machine showing my new design.

The back of the machine is plain and the opposite side presents substantially the same appearance as the side shown.

I claim:

The ornamental design for an X-ray machine as shown and described.

WILLIAM H. THWAITES.
